FRUIT OR VEGETABLE CRATE

Frank D. Thompson, Jr., Cleveland, Ohio, assignor
to Wooden Containers Inc., Cleveland, Ohio, a
corporation of Ohio

Application April 13, 1936, Serial No. 74,003

15 Claims. (Cl. 217—12)

My invention relates to an improvement in folding boxes or crates and in particular boxes or crates for shipping fruit and vegetables, and which may be used again and again for the same purpose, instead of only once as is customary with the usual crate.

One object is to provide means whereby a folding crate may be manufactured as a flat strip of units or connected parts, which, when set up become a complete box except for the top or lid which will be a separate unit to be nailed on.

Another object is to provide means whereby an end strip may be split crosswise and provided with bottom cleats and inverted top cleats and swung into such position as to form the sides of the box.

A further object is to provide a means whereby an additional half unit may be secured to the original strip of units or connected parts by suitable means, which when swung into position forms a middle partition in the box.

Further objects are to provide a folding crate of simple construction and compact form, in which each part or unit is connected to the next part or unit in such manner as to permit facility in assembling, handling and shipping.

Other objects and advantages may be noted from the following specification and its accompanying illustrations, in which—

Fig. 1 is a plan view of the outside of the box as it comes from the machine which applies the cleats and the wire to the panels forming the box.

Fig. 2 shows a fragment of one corner of the bottom and one end of the box as it is being assembled.

Fig. 3 shows a fragment of one end unit and one part of the split unit forming the side unit, the arrow indicating the line of movement in assembling.

Fig. 4 shows the completed connection or union of the two parts shown in Fig. 3.

Fig. 5 is a perspective view of the assembled box, one side secured in position between the two ends and the opposed side just entering its final position.

Fig. 6 is a plan of a modified form showing an additional half panel which forms a center position when assembled.

Fig. 7 shows a fragment of one end and the half unit being assembled.

Fig. 8 is a perspective of the completely assembled modified box.

Fig. 9 is a fragmentary portion of the box showing the narrow cleat on the side panel and a wide cleat on the end panel interlocking.

Fig. 10 is a plan of a second modification showing two opposed ends cut to form sides to the bottom of the box.

Fig. 11 is a perspective of Fig. 10 assembled.

Referring to the drawings, a strip of panel units including an end panel 10, a bottom panel 11, an opposed end panel 12 and a split unit forming two side panels 13 and 14 are connected together by a pair of wires 15 and 15a at the side edges of each panel as shown in Fig. 1 and said wires form, in effect, flexible connections or hinges between the panels.

The end panel 10 has a pair of cleats 16 and 17 attached at the side edges respectively of the outside of the panel, the outer ends of the cleats 16 and 17 having tenons 16a and 17a respectively and the inner ends of said cleats having mortises 16b and 17b respectively, the mortise or inner end of the cleats projecting somewhat beyond the adjacent edge of the panel 10.

The bottom panel 11 has a pair of cleats 18 and 19 attached at the side edges respectively of the outside of the panel, the ends of the cleats 18 and 19 adjacent to the end panel 10 having tenons 18a and 19a respectively, and the opposite ends of said cleats having mortises 18b and 19b respectively.

The opposed end panel 12 has a pair of cleats 20 and 21 attached at the side edges respectively of the outside of the panel the ends of said cleats adjacent to the bottom panel 11 having tenons 20a and 21a respectively and the opposite ends of the said cleats having mortises 20b and 21b, both ends of said cleats extending beyond the said panel 12, substantially as shown in Fig. 1.

The split panel section 13 has a cleat 22 attached at its outer edge and a reinforcing cleat 24 attached by suitable means at its inner edge adjacent the center split and the panel section 14 has a cleat 23 attached at its outer edge and a reinforcing cleat 25 attached at its inner edge adjacent the center split.

The inner ends of the cleats 22 and 23 have transverse or right angle tenons 22a and 23a, and the opposite ends of said cleats have transverse mortises 22b and 23b, the inner ends of said cleats extending to the ends of the split panels 13 and 14 substantially as shown in Fig. 1.

The wires 15 and 15a are attached on the outside surface of the panels 10, 11 and 12 at the edges respectively opposed to the cleats 16, 18, and 20 at one edge and 17, 19 and 21 at the other edge, the wire 15 being attached on what becomes the inside surface of the split panel section 13 opposed to the cleat 22, while the wire 15a is at-

tached on what becomes the inside surface of the split panel section 14, opposed to the cleat 23. These wires are secured continuously to the panels by staples 24 or the like at intervals as shown in Fig. 1.

In assembling or setting up the box, the mortises 16b and 17b in the cleats 16 and 17 of the end panel 10 receive the tenons 18a and 19a on the cleats 18 and 19 of the bottom panel 11 and 10 are engaged therewith as the assembling progresses; the mortises 18b and 19b in the cleats 18 and 19 of the bottom panel 11 register with and engage the tongues 20a and 21a in the cleats 20 and 21 of the opposed end panel 12 in a like manner to those hereinabove described.

The section 13 and 14 of the split panel are swung or partially rotated outwardly until the transverse tongues 22a and 23a register with and engage the grooves 20b and 21b in the ends of the 20 cleats 20 and 21 of the opposed end panel 12; the transverse mortises 22b and 23b at the same time, register with and engage the tenons 16a and 17b in the cleats 16 and 17 of the end panel 10; the said split panel sections thus forming side panels 25 and completing the unit assembly, the wire connections permitting the panels 10 and 12 to be swung up to vertical and the sections 13 and 14 to be twisted and swung over into place, the cleats 22 and 23 of the split sections 13 and 14 then being 30 coming top cleats while the reinforcing cleats 24 and 25 of the split panel sections 13 and 14 respectively become bottom cleats and engage the grooves or recesses 26 and 27 in the cleats 17 and 21 and similar grooves in the cleats 16a and 20a 35 in the end panels respectively.

The opposed ends of the wires 15 and 15a are then twisted together as shown substantially in Fig. 5. The box may then be filled and a top nailed on for shipping.

40 In the modification, a further half panel section 30 is added adjacent the outer edge of the end panel 10a and secured to the original strip of units by a center wire 15b as shown in Fig. 6. The half panel section 30 has a cleat 31 attached 45 at its top edge having tenons, 31a at one end and 31b at the opposite end; and a reinforcing cleat 32 is attached at the outer edge of said split panel section 30.

In assembling the additional half section 30 50 with the original box, the wire 15a is cut at 33, the panel 30 being secured only by the wire 15b; and a panel 30a is then attached to the panel 30 as shown in Figs. 7 and 8 and the double panel is inserted in the middle of the box, the tongues 55 31a and 31b registering with and engaging the mortise 34a in a cleat 34 secured at the middle of the end panel 10 and a groove 35a in a cleat 35 secured through the center of the opposed end panel 12, respectively, thus forming a center partition to the crate or box.

A cleat 36 secured in the center of the panel 11 60 may be used in place of the cleats 34 and 35 of the panels 10 and 12 to secure the same results. This is indicated by dotted lines as shown in Figs. 6 and 8.

The opposite ends of the wires 15, 15a and 15b are then twisted together as shown in Fig. 8.

This modified form shown in Figs. 6 to 9 inclusive, provide narrow cleats 37, 38, 39 and 40 70 which replace cleats 16, 17, 20 and 21 of the end panels 10a and 12a.

Cleats 41, 42, 43 and 44 are substituted for the cleats 18, 19, 22 and 23 of the panel 11 and split panel sections 13 and 14 respectively of the orig-

inal box, and have a tongue projecting therefrom off center as shown, the longer end portion 38b extending outward to the outer edge of said cleats 42 and 43 respectively.

The reinforcing cleats 24a and 25a of the split panel sections 13a and 14a also are extended outward to contact the bottom edge of the panels 10 and 12, the narrow cleats eliminating the necessity for the slot 21 shown in the original box, as the wider cleats 24a and 25a when secured to the narrow cleats 41, 42, 43, and 44 respectively, retain the panels 13a and 14a securely in a vertical plane.

A second modification is shown in Figs. 10 and 15 11, the end panels 45 and 47 and the bottom panel 46 extending to the end of their cleats 50 to 55 inclusive, and the split panel sections 48 and 49 which form the side panels are cut longer, one only being attached at each end of the strip, at 20 opposed sides.

The short panel section 48 has a cleat 56 attached at its upper end, and the opposed short panel section 49 has a cleat 57 attached at its lower end, each panel being twisted or swung around and inserted to form the sides, the tenons 25 and mortises registering and interlocking to form the box shown assembled in Fig. 11, the ends and sides extending to the bottom within the box thus formed and the wires twisted in the positions 30 shown.

The construction provides a knockdown box which can be made and supplied in flat condition with all the parts permanently connected together, and the wire connections permit the ends 35 to be swung up and the side panels 13 and 14 to be swung over and twisted or partially turned to fit between the end panels, the tenons and mortises in all the panels being engaged together to form a rigid structure, and the ends of the wires 40 twisted together to hold the parts in place. By untwisting the wires the units or panels can be 45 disengaged and laid down flat again if desired. And so the box is capable of repeated use by being knocked down and being set up indefinitely.

Various other modifications are possible within 45 the scope of the invention.

I claim:

1. A knockdown box comprising a bottom panel, an end panel connected to each end thereof, and side panels connected to the outer end of one of the end panels, the connections between the respective panels being sufficiently flexible to permit the end panels to be swung up in opposed relation and the side panels to be swung into position between the end panels, when the box 55 is set up.

2. In a knockdown box or crate the combination of a bottom panel, end panels at each end of the bottom panel, side panels at the outer end of one end panel, and flexible connections between the respective panels comprising wires which may be bent to permit the box to be set up.

3. In a folding box or crate, the combination stated in claim 2, the wires being located adjacent opposite side edges of the panels.

4. In a folding box or crate, the combination stated in claim 2, the bottom and end panels being provided at their side edges with cleats having mortises and tenons which interlock when the box is set up.

5. A knockdown box comprising a string of end, bottom and side panels arranged in a line in a single plane when knocked down and connected to each other by flexible connections per-

mitting the end panels to be swung up to vertical position and the side panels to be swung over into position between the end panels.

6. A folding box comprising a single line of end, bottom and side panels in a single plane when unfolded, and wire connections between the panels extending along the side edges thereof.

7. A folding box as set forth in claim 6, the panels having cleats extending along the side 10 edges thereof.

8. In a folding box or crate, the combination of a bottom panel, a side panel at each end of the bottom panel, and a pair of end panels at the outer end of one of the side panels, flexible connections between the bottom panels and the end 15 panels and twistable connections between the side panels and the end panel.

9. A folding box or crate as set forth in claim 8, said connections comprising wires extending 20 along the edges of the panels and across the joints therebetween.

10. In a folding box or crate the combination stated in claim 8, the panels having cleats extending along side edges thereof and provided 25 with tenons and mortises which interlock when the box is set up.

11. A folding box comprising a string of bottom, side and end panels arranged when knocked down in a single line and in a single plane, and

flexible connections between the various panels bendable to permit the end panels to be set up to vertical position and the side panels to vertical position between the end panels.

12. A folding box comprising a bottom panel, 5 end panels at opposite ends of the bottom panel, a pair of side panels at the outer end of one end panel, a partition panel at the outer end of the other end panel, and wire connections between the respective panels, bendable to permit the box 10 to be set up.

13. A folding box comprising a bottom panel, end panels at opposite ends of the bottom panel, and a side panel at the outer end of each end 15 panel, and wire connections between the respective panels bendable to permit the panels to be set up.

14. A folding box as in claim 13, and cleats at the edges of the panels having mortises and tenons which interlock when the box is set up. 20

15. In a folding box or crate comprising a row of bottom, end and side panels arranged in a line and in a single plane when unfolded, and a pair of wires extending along opposite edges of the respective panels and across the joints between 25 them, the wires being bendable to permit the panels to be set up in proper position to form a box.

FRANK D. THOMPSON, JR.
